UNITED STATES PATENT OFFICE

173,008

COMBINED AUTOMOBILE FENDER AND REAR QUARTER PANEL

Richard F. Baird, Oak Park, and Frederick Reynolds, Bloomfield Hills, Mich., assignors to Chrysler Corporation, Highland Park, Mich., a corporation of Delaware

Application June 24, 1953, Serial No. 25,631

Term of patent 7 years

(Cl. D14—6)

To all whom it may concern:

Be it known that we, Richard F. Baird and Frederick Reynolds, citizens of the United States, residing in the cities of Oak Park and Bloomfield Hills, respectively, county of Oakland, and State of Michigan, have invented a new, original, and ornamental Design for a Combined Automobile Fender and Rear Quarter Panel, of which the following is a specification, reference being had to the accompanying drawing, forming part thereof, in which:

Fig. 1 is a side elevational view of a combined automobile fender and rear quarter panel showing our new design;

Fig. 2 is a rear elevational view thereof; Figs. 3 and 4 are sectional views taken on the lines 3—3 and 4—4 respectively, of Fig. 1; and

Fig. 5 is a rear perspective view thereof on a reduced scale.

The broken line showings in the drawing figures are for illustrative purposes only.

We claim:

The ornamental design for a combined automobile fender and rear quarter panel, substantially as shown and described.
